UNITED STATES PATENT OFFICE

122,489

DESIGN FOR A MAT OR SIMILAR ARTICLE

Vera Way Marghab, New York, N. Y.

Application August 1, 1940, Serial No. 94,104

Term of patent 14 years

To whom it may concern:

Be it known that I, Vera Way Marghab, a citizen of the United States, residing at New York, county and State of New York, have invented a new, original, and ornamental Design for a Mat or Similar Article, of which the following is a specification, reference being had to the accompanying drawing, forming part thereof, wherein the figure is a plan view of a mat or similar article showing my new design.

I claim:

The ornamental design for a mat or similar article, substantially as shown.

VERA WAY MARGHAB.
